UNITED STATES PATENT OFFICE.

WILLIAM H. PARMELEE, OF DURHAMVILLE, NEW YORK.

DEVICE FOR REMOVING FAUCETS FROM CASKS.

SPECIFICATION forming part of Letters Patent No. 365,404, dated June 28, 1867.

Application filed October 5, 1886. Serial No. 215,336. (No model.)

To all whom it may concern:

Be it known that I, WILLIAM H. PARMELEE, a citizen of the United States, residing at Durhamville, in the county of Oneida, State of New York, have invented certain new and useful Improvements in Devices for Removing Faucets from Casks, of which the following is a specification, reference being had therein to the accompanying drawings.

My invention relates to devices for removing faucets from barrels and kegs, and for other purposes.

The object of my invention is to provide a means whereby the faucets can be removed from barrels and kegs without breaking or injuring the same.

Referring to the drawings, Figure 1 is a view in perspective of one end of a barrel with the faucet therein and my appliance placed thereon in position for use. Fig. 2 is a sectional end view, taken on the line *x x* of Fig. 1.

A indicates the barrel or keg, in the end of which the faucet B is inserted in the usual manner. The faucet B is made of wood, and is of the common and well-known form, and need not be further described in this connection.

C is a piece of metal or wood having its under side hollowed out or concave, so as to conform or partially conform to the curvature or convexity of the periphery of the faucet, and is provided with a lug, D, having an aperture therethrough to receive the ring E.

The ring E may be made of metal or of a cord or rope of any suitable fibrous substance of suitable strength.

F is a wedge having one side concave and adapted to conform to the convex surface of the faucet, said wedge being provided with an arm or projection, G, to receive the blows of the hammer or mallet by which the wedge is driven into the loop or ring.

It will be noticed that as the wedge F is driven into the loop the plate or top bearing, C, is drawn down onto the top of the faucet, and that as the wedge is still farther driven the faucet will be drawn out of its seat in the cask.

In operating the device the barrel is rolled over so as to bring the faucet on top, in order that the operator can more readily strike the arm G of the wedge F; and, as a further safeguard to prevent the faucet from breaking off at the small end, the operator should take hold of the outer end of the faucet and exert a slight upward pressure at each stroke of the hammer, and in this way the faucet can be readily withdrawn without injury.

What I claim, and desire to secure by Letters Patent, is—

An appliance for removing faucets from barrels, consisting of a plate for clamping one side of the faucet, a ring or loop connected to said plate and surrounding the faucet, and a wedge in between the ring and faucet, as set forth.

In testimony whereof I affix my signature in presence of two witnesses.

WILLIAM H. PARMELEE.
